UNITED STATES PATENT OFFICE.

DILLON E. MAPOTHER, OF LOUISVILLE, KENTUCKY.

DESIGN FOR A CONFECTION.

SPECIFICATION forming part of Design No. 21,760, dated August 9, 1892.

Application filed March 7, 1892. Serial No. 424,091. Term of patent 14 years.

To all whom it may concern:

Be it known I, DILLON E. MAPOTHER, of Louisville, in the county of Jefferson, in the State of Kentucky, have invented a new and 5 useful Design for Confectionery, of which the following, taken in connection with the accompanying drawings, is a full, clear, and exact description.

My invention is a design for confectionery, 10 as will be hereinafter fully pointed out.

In the annexed drawings, Figure 1 is a perspective view of the design, and Fig. 2 is a bottom plan view.

The leading feature of my design consists 15 in a raised scalloped surface having an irregular outline.

By referring to the drawings it will be noticed that the upper surface A of the lump or 20 article of confectionery is somewhat irregular and is inclined toward the sides, while the edges B are all on the bottom of the lump

and are slightly separated, thus imparting to the lump the appearance and form of a small sea-shell. In order to increase the effectiveness of this appearance, corrugations C are 25 formed upon the surface of the lump, as shown.

Having thus described my invention, what I claim, and desire to secure by Letters Patent, 30 is—

The design for a confection, herein described and shown.

In testimony whereof I have hereunto signed my name, in the presence of two attesting witnesses, at Louisville, in the county of Jefferson, in the State of Kentucky, this 2d day 35 of March, 1892.

DILLON E. MAPOTHER.

Witnesses:

FREDERICK H. GIBBS,
